LOCK FOR SLIDE FASTENER SLIDERS

Albert Weber, Edgewood, R. I.

Application October 16, 1944, Serial No. 558,796

2 Claims. (Cl. 24—205.14)

1

This invention relates to a slider for slide fasteners and more particularly to a locking device for such slider.

Various locking devices have been provided for the slider of slide fasteners so as to prevent the slider from moving along the slide fasteners to separate or close the same except when the lock is withdrawn by some manual means. Such locking devices frequently provide a point to extend between the fasteners so as to prevent motion and this point, if not completely withdrawn as it slides over fasteners, may become dull and the point so worn as to become non-effective. In some cases locking constructions are made of channel shaped parts requiring bending or drawing operations. In some cases the pull tab is flexibly connected to the slider in such a way that it may be pulled upon to move the locking member to release position. Sometimes resilient means are provided for moving the locking member in one direction, such for instance as to locking position while depending upon the movement of the tab for swinging the locking member against the resiliency of the spring.

One of the objects of this invention is to provide a locking member for a slider which may be formed of a solid piece of material.

Another object of this invention is to provide a locking member for a slider which will have no sharp point necessary to engage between fasteners for locking the same in position.

Another object of this invention is to provide a positive means for holding a blunt or rounded end of a locking device against slide fasteners so as to apply a sufficient pressure thereon to prevent movement of the slider body.

Another object of this invention is to provide an arrangement whereby no resilient means is required.

Another object of this invention is to provide a tab which may effectively provide a lever extension from the locking member for manipulating the locking member.

Another object of this invention is to provide a tab which may swing with reference to the locking member and act as a wedge to move the locking member from locked position.

Another object of this invention is to provide a simple construction which may be easily and quickly assembled and the parts of which are relatively simple that they may be made with a minimum of tool operations.

With these and other objects in view, the invention consists of certain novel features of construction, as will be more fully described and particularly pointed out in the appended claims.

In the accompanying drawings:

Fig. 1 is a top plan view of a series of slide fasteners with a slider mounted thereon and the pull tab also shown in position;

2

Fig. 2 is a sectional view on line 2—2 of Fig. 1; Fig. 3 is a view showing the locking member as moved by the tab to release position;

Fig. 4 is a view similar to Fig. 3 but showing the tab as locked with the locking member for moving the same to locking position;

Fig. 5 is a sectional view similar to Fig. 2 but on a greatly enlarged scale and with the slide fasteners removed;

Fig. 6 is a top plan view of the pull tab alone.

In proceeding with this invention a locking member is provided which is pivoted on the slider and which may be moved by a pull tab into a position so that detent and recess means will hold it in that position, such position being that of pressing against the slide fasteners to prevent movement of the slider. The construction is also arranged so that when the tab is rocked through substantially ninety degrees a wedging action takes place between it and the locking member so as to pry the locking member from locking position. The parts are such that they may be formed of solid construction and relatively strong although light in weight while at the same time they are of simple formation.

With reference to the drawings, I show a pair of fabric strips 10 and 11 upon which there is an edging 12 and each of which has mounted thereon a slide fastener 13 of such a construction that the projecting part 14 of each fastener will fit into a recess on the under side of a similar fastener on the opposite strip while itself receiving the next adjacent fastener on the opposite strip in a well known manner.

35 In order that these slide fasteners may be operated there is a slider 15 comprising a body formed of two plates 16 and 17 held together by a suitable post construction 18 which acts as a fastener separator. This slider is provided with

40 suitable flanges for guiding it in its movement for closing or separation of the slide fasteners. In the upper plate 16 I provide a hole or opening 20 and upon this plate there is also provided ears

45 between which a locking member 22 is pivoted on the pin 23. The locking member is shaped, as shown in Fig. 5, having a rounding portion 25 having a portion 24 extending therefrom so as to engage the plate 16 and form a stop limiting the

50 rocking movement about the pivot in one direction. The opposite end of this member 22 is provided with a slot 26 formed partially by a hook 27 and leaving an opening 28 from this slot on the side toward the plate 16. One wall 29 of this slot 26 is substantially straight while the wall 39 of the slot 26 which also forms an edge of the hook is slightly curved as shown in Fig. 5. The outside or back of the hook is provided with a

55 notch 31 for the reception of a detent 32 formed on the plate 16 adjacent the opening 20. When these parts are in engagement the locking mem-

ber is held firmly against the slide fasteners to prevent a movement of the slider therealong.

The pull tab designated generally 35 consists of a rectangular sheet of stock which has a hole 38 punched therein. The width of this hole 36 is of a dimension to receive the member 32 therethrough while the cross piece 37 between one end of the hole and the end 38 of the pull tab is of a dimension to loosely fit within the slot 26. This portion 37 will engage at its end 38 with the straight wall 29 while at a point inwardly from its edge 39 it will engage and rock about the rounded surface 30, until its edge 39 is in engagement with the end 40 of the slot 26. The sizing of the parts is such as to provide substantially a three-point contact at spaced locations for the pull tab and the locking member 22 so that this pull tab acts as a lever extension of the locking member which, in its movement toward closing position, is substantially rigid and will move the locking member 22 so that the detent will snap by the rounded end 41 of the hook and will enter the recess 31 to hold the locking member firmly in locking position.

The opening 28 is of such a size and the rounded surface 30 is of such shape that when the pull tab 35 is moved upwardly its end 38 will leave the surface 29 and it will rock about the surface 30 until its corner 43 passes through the opening 28 and engages the plate 16. At this point the corner of the edge 39 will engage the upper straight surface 29 of the recess or slot and by continued upward movement of the pull tab 35 these diagonally opposite corners will slide along the surfaces which they engage acting as a pry or wedge to swing the member 22 clockwise about its pivot thus withdrawing the hook-shaped portion which presses against the slide fasteners from engagement therewith and moving this recess and detent out of engagement. When the locking member has been so positioned the slider will be free to move along the slide fasteners in either direction.

In order that the pull tab may serve to move the slide fasteners to open position the limiting stop 24 which engages the plate 16 serves very well to prevent too great an opening or swinging of the locking member and thus this locking member may be used as a means for holding the pull tabs so that it may act for applying pressure on the slider to run the slider to open position or to closed position.

I claim:

1. A slider for slide fasteners of the class de-

scribed comprising a slider body, a locking member pivoted on said body and having a locking projection of a length greater than the spacing between adjacent interlocking elements of the fastener to engage the slide fasteners, readily separable latching means between said member and body to hold said member against said slide fasteners in locking position, said locking member being provided with a slot, a pull tab having a portion to enter said slot and engage the walls thereof on opposite sides and at one end thereof for in effect providing a continuation of the member as a lever for rocking the member to locked position, said latching means being readily operable upon rocking of the member.

2. A slider for slide fasteners of the class described comprising a slider body, a locking member pivoted on said body and having a locking projection to engage the slide fasteners, readily releasable latching means between said member and body to hold said member against said slide fasteners in locking position, said locking member being provided with a slot having an open end, a pull tab having a portion to enter said slot and engage the walls thereof on opposite sides and at one end thereof for in effect providing a continuation of the member as a lever for rocking the member to locked position, said latching means being readily operable upon rocking of the member, said slot opening on the side toward the body for engagement of the end of the tab with the body, said tab being of a size to act as a wedge between the body and wall of the slot to pry the member from locking position upon rocking the tab away from the body.

ALBERT WEBER.
